UNITED STATES PATENT OFFICE.

JOSEF ANTON GUBELMANN, OF RAPPERSWIL, SWITZERLAND.

LOOM-SHUTTLE.

1,099,357.

Specification of Letters Patent.

Patented June 9, 1914.

Application filed October 5, 1911. Serial No. 652,902.

To all whom it may concern:

Be it known that I, JOSEF ANTON GUBELMANN, a citizen of the Republic of Switzerland, residing at Rapperswil, Switzerland, have invented new and useful Improvements in Loom-Shuttles; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 The subject of my invention is a loom shuttle in which the part to place the bobbin on is arranged to be elastically movable in a longitudinal direction by means arranged within the head of the spindle.

20 Heretofore the spindle head has been detachably connected to the shuttle spindle; these often become loose and either fly out or cause thread breakages by being too loose, but the most serious inconvenience results from the accumulation of lint and fiber around the spring that yieldingly holds the bobbin holding tube. Another difficulty has been that the springs holding these tubes were quickly stretched beyond their elastic 25 limits by the heavy blows on the shuttle by the picker staff. These difficulties I have overcome by using a spindle that is not detachable from the spindle head, by inclosing the spring for the bobbin tube within the 30 spindle head and by limiting the movement of the spring.

Some forms of construction according to this invention are illustrated in the accompanying drawings in which—

40 Figure 1 is a longitudinal section through a part of a first construction, Fig. 2 a section on line A—B of Fig. 1, Fig. 3 a longitudinal section through a part of another construction, Fig. 4 a section on line C—D of Fig. 3, Fig. 5 a longitudinal section through a part of a third construction, Fig. 6 a section on line E—F of Fig. 5, Fig. 7 a longitudinal section through a part of a fourth construction, Fig. 8 a section on line G—H of Fig. 7, Fig. 9 a longitudinal section through a part of a fifth construction, Fig. 10 a front view of the same, Fig. 11 a longitudinal section through a part of a sixth construction. Fig. 12 a front view of

the same. Fig. 13 a longitudinal section through a part of a seventh construction.

In the first form of construction *a* is the spindle secured to its head *c* which is rotatable about the pivot *g* and under the action of a spring *h* to normally hold the spindle 60 in the position shown. The spindle *a* is surrounded by an elastic slotted tube *b*, which is expanded in its middle portion and open on the front end. The bobbin is placed on the tube *b* and is frictionally held thereon by the 65 expanded middle portion. The tube *b* is provided on its rear end with a flanged border *d*, against which presses one end of a spring *f*, the other end of which presses against a screw-plug *i*, which closes the hole 70 space in the head of the spindle and containing the spring *f* and the end of tube *b* having the flanged border *d*. This construction enables the tube with the bobbin to move elastically in a longitudinal direction 75 when the shuttle bounds against the ends of its course and prevents the bobbin from being thrown off. The arrangement of the means for producing this effect within the head of the spindle prevents the spring *h* 80 from exerting a braking action on the tube *b*.

In the form of construction illustrated in Figs. 3 and 4 the tube *b* is closed on the front forming an air cushion between the tube end and spindle end.

85 In the form of construction shown in Figs. 5 and 6 the shape of the head *c* of the spindle differs from the previously described constructions. One leg of the spring *h* rests against an inner vertical wall of the 90 shuttle, while the other leg acts against the rear end of the head *c* of the spindle.

In the form of construction of Figs. 7 and 8 the head *c* of the spindle is removably clamped between two springs *m*.

95 In the form of construction of Figs. 9 and 10 the spindle *a* itself is the part to place the bobbin on. For this purpose the spindle *a* is provided on that end which is displaceably supported within the head *c* 100 of the spindle with a collar *n* against which presses the end of the spring *f*. Also in the form of construction of Figs. 11 and 12 the spindle *a* is the part to place the bobbin on, the spindle being split and expanded to become elastic. The collar *n* is provided with a transverse cut *o* by which it engages a pin *q* secured to the head *c* 105

thus being prevented from turning. A spring *p* fixed to the spindle *a* secures the socket *r* of the bobbin in position.

In the form of construction of Fig. 13
5 the spindle *a* and the tube *b* are conical.

In the forms of constructions in which
there is arranged a tube, there may also be
provided a spring on the tube such as *p*.

The spindle can be cylindrical or conical,
10 also the tube can be cylindrical or conical.
The tube can be open or closed on the front.
The tube can be split or not split.

I claim—

15 1. A loom shuttle having a spindle head
attached thereto and a spindle extending
from the head, in combination with a bob-
bin tube mounted on the spindle and ex-
tending within the head and a spring en-
tirely inclosed within the head and acting
20 on said tube to permit longitudinal move-
ment of said tube.

2. In a loom shuttle; a pivoted spring-
held spindle head having a recess therein,

a spindle secured to the head and project-
ing from the recess, a bobbin-supporting tube
25 mounted on the spindle, and means inclosed
within said head to yieldingly hold the tube
on the spindle to permit longitudinal move-
ment of said tube with respect to the
spindle.

3. In a loom shuttle, a spindle head hav-
ing a recess therein, a spindle secured to the
head and projecting from the recess, a bob-
bin-supporting tube mounted on the spindle
and having a flanged end, a closure for the
35 recess through which the spindle and tube
project and a coil spring surrounding the
tube between the flanged end and closure.

In testimony that I claim the foregoing
as my invention, I have signed my name in
40 presence of two subscribing witnesses.

JOSEF ANTON GUBELMANN.
